METHOD OF ELECTRICALLY EXPLORING
BORE HOLES

Eugene McDermott, Dallas, Tex.

Application March 21, 1934, Serial No. 716,656

4 Claims. (Cl. 175—182)

This invention relates to new and useful improvements in methods of exploring bore holes in the surface of the earth and it has for its principal object to provide a method for determining electrically the characteristics of rocks and other sub-surface formations below the earth's surface without requiring the removal of the conventional drilling equipment from the bore hole.

Another object of the invention is to provide a medium by which to overcome the difficulties encountered in conventional methods, which require that the drill stem and bit be removed from the bore hole or the permanent installation in the drill stem of accessory devices such as an insulated conductor which latter interferes materially with the flow of drilling fluid. The present invention requires neither of the foregoing operations for its successful performance.

The present invention contemplates a method wherein conventional rotary drilling equipment may be used with but a few simple modifications, namely; a vertical hole through the end of the drilling bit through which is passed a small cylindrical electrode, the latter being suspended on an insulated conducting cable which is lowered into the drill stem from the earth's surface.

Since there is at least one hole in the standard drilling bit to permit the passage of drilling fluid, the same hole may be used to pass the electrode as well as the drilling fluid provided this hole is bored vertically in the drilling bit. If not desirable to use a vertical hole, this can be plugged in any obvious and suitable manner.

With the foregoing objects as paramount, the invention has particular reference to its salient features of construction, arrangement of parts and steps in the method, which will become manifest as the description proceeds, taken in connection with the accompanying drawings, where-

40 in:

Figure 1 diagrammatically illustrates a standard rotary drill stem and drill bit showing the invention applied.

Figure 2 is a fragmentary detail view of one 45 form of electrode.

Figure 3 is a modified form of the invention.

Figure 4 is a further modified form of the invention, and

Figure 5 is yet another modified example.

50 Continuing with a more detailed description of the drawings, 1 designates the standard rotary drill stem having a drill bit 2 attached to its lower end. The drill stem 1 passes through a standard rotary table 3 defined to impart rotation to the drill stem and the bit. The drill bit

may be lifted off the bottom of the bore hole by means of the clamp 4, shown in Figure 1.

The invention is comprised primarily of an electrode 5 of copper or any other suitable conducting material and is suspended from the end 5 of a conducting cable 6 which is completely covered with an insulating material 7, shown in Figure 2.

The cable 6 is passed over a pulley 8 and is wound upon a drum or reel 9 which allows it to 10 be lowered into the bore hole 10. The opposite end of the cable 6 is free and this free end of the cable is connected to one terminal of a battery 11. The other terminal of the battery 11 is connected through an ammeter 12 to a plurality of ground rods, 13—14, to obtain low resistance connection to the ground, a voltmeter 15, arranged as shown, is employed to measure the battery voltage.

Current will thus flow through the ground from 20 the electrode 5 in the hole 10 to the ground rods 13—14 at the surface. As the principal resistance to the flow of current will be near the electrode 5 in the hole, any change in the character of the rocks or other formations, the electrode 5 25 penetrates will alter the flow of current and will result in a change of current flowing through the ammeter 12. It will be understood that other and well known indicating devices may be employed.

Figure 4 shows an example of the manner in which the ground rods 13 and 14 may be omitted, the circuit including the drill stem 16 and bit 17. In this case the principal resistance to the flow of current in the circuit is that existing between 35 the electrode 18 and bit 17. It will be understood that the bit 17 and electrode 18 are suitably spaced apart prior to recording the readings of the ammeter 19 and voltmeter 20.

Figure 5 illustrates a further modification of 40 the invention in which the circuit is completed by employing both the ground rods 21 and 22 as well as the drill stem 23 and bit 24. The latter is spaced apart from the electrode 25, after which the readings of ammeter 26 and voltmeter 45 27 are recorded.

Previous research has shown satisfactorily that a clay, for example, carrying highly mineralized water will have a lower resistance than a sand carrying fresh water. Also, a sand carrying oil 50 or gas will have a very high resistance. As a result, the indications of the meter at the surface may be used to interpret changes in rock character in the neighborhood of the bit 2.

In practice, it may be preferred that the elec- 55

trode be primarily suspended a predetermined distance below the drill bit after the drill stem has been elevated by surface equipment a distance of the approximate length of one section 5 thereof. Then the drill stem and electrode may be simultaneously moved up and down in the hole, relative to the bottom thereof until observations are satisfactorily completed.

Instead of inserting a battery in the system as 10 indicated in the drawings and as described, the battery and ammeter may be omitted and a potentiometer may be used to indicate the self voltage of the rocks in the bore hole 10. In this case, the potentiometer such as shown in Figure 15 3 is inserted between the conducting cable 6 and the ground rod or drill stem 13—14 and 1 respectively.

Manifestly, the construction shown is capable 20 of some modification and such modification as is considered within the scope and meaning of the appended claims is also considered within the spirit and intent of the invention.

What is claimed is:

1. The method of electrically exploring bore 25 holes which consists in elevating the hole boring tool a predetermined distance above the bottom of the bore hole in lowering an electrode through the rotary drill stem and through a hole in the drill bit of the hole boring mechanism, in suspending said electrode in the bore hole operatively below said drill bit and insulating the same therefrom, in electrically connecting said electrode with a battery and suitable indicating instruments and the surface of the ground and observing the change of voltage and current by 35 means of said indicating instruments as the position of the electrode is changed in the hole.

2. The method of electrically exploring bore 40 holes which consists in elevating the hole boring tool a substantial distance above the bottom of the bore hole in lowering an electrode through the rotary drill stem and through a hole in the

drill bit of the hole drilling mechanism and suspending said electrode in the bore hole substantially below the drill bit and insulating said electrode from said drill bit, in electrically connecting said electrode with a source of electrical energy and suitable indicating instruments and the drill stem and observing the change of electrical characteristics by means of the said indicating instruments as the position of the electrode is changed in the hole. 10

3. The method of electrically exploring bore holes which consists in elevating the hole boring tool a predetermined distance above the bottom of the bore hole, in lowering an electrode through the rotary drill stem and through a hole in the 15 drill bit of the hole boring mechanism, in suspending said electrode in the bore hole operatively below said drill bit and insulating the same therefrom, in electrically connecting said electrode through suitable indicating instruments 20 with the surface of the ground and with the drill stem, and in observing the change of electrical characteristics by means of said indicating instruments as the position of the electrode is changed in the hole. 25

4. The method of electrically exploring bore holes which consists in elevating the hole boring tool a substantial distance above the bottom of the bore hole, in lowering an electrode through the rotary drill stem and through a hole in the 30 drill bit of the hole boring mechanism, in suspending said electrode in the bore hole operatively below said drill bit and insulating the same therefrom, in electrically connecting said electrode through suitable indicating instruments 35 and the drill stem, and in observing the change of electrical characteristics by means of the said indicating as the electrode and drill stem are simultaneously moved relative to the bottom of the bore hole. 40
